UNITED STATES PATENT OFFICE.

CHARLES L. WIEDRICH, OF BUFFALO, NEW YORK, ASSIGNOR TO THE
UNITED HAME COMPANY, OF SAME PLACE.

DESIGN FOR A HAME-BODY.

SPECIFICATION forming part of Design No. 34,029, dated February 5, 1901.

Application filed December 24, 1900. Serial No. 40,988. Term of patent 7 years.

To all whom it may concern:

Be it known that I, CHARLES L. WIEDRICH, a citizen of the United States, residing at Buffalo, in the county of Erie and State of New York, have invented and produced a new and original Design for a Hame-Body, of which the following is a specification, reference being had to the accompanying drawings, forming a part thereof.

This design relates to the shape or configuration of hames.

In the accompanying drawings, Figure 1 is a perspective view of a hame embodying my design. Fig. 2 is a cross-section thereof.

The leading feature of my design consists of a hame-body having a convex front face, a flat rear side, a convex outer side, and a concave inner side.

Referring to the drawings, A is the body of

the hame, which has the customary compound curve.

b is the convex front face of the hame-body; c, its flat rear side; d, its back or outer side, which is convex, and e its inner side, which faces the roll of the horse-collar and which is concave. The groove or depression which forms the concave side of the hame extends nearly from end to end of the hame, as shown in Fig. 1.

What I claim is—

The design for a hame-body, substantially as herein shown and described.

Witness my hand this 20th day of December, 1900.

CHARLES L. WIEDRICH.
